Victor J. Evans

Attorney

UNITED STATES PATENT OFFICE.

KATHERINE W. WADE, OF SAN FRANCISCO, CALIFORNIA.

DESIGN FOR A NOVELTY DOLL.

Application filed September 5, 1924. Serial No. 10,682. Term of patent 7 years.

To all whom it may concern:

Be it known that I, KATHERINE W. WADE, a citizen of the United States of America, residing at San Francisco, in the county of San Francisco and State of California, have invented a new, original, and ornamental Design for Novelty Dolls, of which the following is a specification, reference being had to the accompanying drawing, forming a part thereof.

The figure is a perspective view of a doll illustrating my new design.

I claim:—

The ornamental design for a novelty doll, as shown.

KATHERINE W. WADE.
